UNITED STATES PATENT OFFICE.

JOHN M. DUNN AND WILLIAM E. SIDWELL, OF NORWALK, OHIO.

STEAM-BOILER.

SPECIFICATION forming part of Letters Patent No. 342,738, dated May 25, 1886.

Application filed November 20, 1885. Serial No. 183,422. (No model.)

To all whom it may concern:

Be it known that we, JOHN M. DUNN and WILLIAM E. SIDWELL, citizens of the United States, residing at Norwalk, in the county of Huron and State of Ohio, have invented certain new and useful Improvements in Steam-Boilers, of which the following is a specification, reference being had therein to the accompanying drawings.

10 Our invention relates to steam-boilers, and has for its object the provision of a simple and efficient heater which shall have the proper circulation of water through it and very thorough circulation of heat and flame around it.

15 The heater consists of a curved water back or chamber mounted directly over the rear end of the fire-chamber in such way as to receive the full force of the escaping flame and heat against it, and shall cause the same to pass down under it and then up over it before escaping. This heater is attached to the sides of the boiler. The boiler is of the return-flue pattern, and has the water-chamber or boiler proper surrounding the fire-box, which latter is located centrally in the structure, with grate-bars placed in it, and provided with suitable doors to the exterior of the boiler. The arrangement of circulation-pipes for the boiler and heater is such as to cause the cold water to be drawn from the bottom of the boiler, and after becoming heated in the heater to be delivered into the boiler at the top. This obviates the difficulty usually encountered in having the heat gradually work its way down in the boiler, and enables us to accelerate the heating. The construction by which we effect these objects is illustrated in the accompanying drawings, and hereinafter described, and 20 pointed out in the claims.

25 In the drawings, Figure 1 is a central longitudinal section of our improved boiler. Fig. 2 is a front elevation of the same, and Fig. 3 a rear elevation with the end plate removed. Fig. 4 is a plan view of a portion of the boiler, showing the manner of making connection between heater E and boiler at the top.

30 Similar letters of reference indicate corresponding parts in all the figures where they occur.

A is the body of the boiler, which is divided into the fire-box B and water-chamber C by the

interior cylinder, D. The water-chamber C is bounded at a distance from each end of the boiler body by disks or plates C'C*, which serve 55 at the same time as supports for the fire-cylinder D. This arrangement leaves a fire-space, b, at the rear end, into which the fire-box B opens, and a similar space, b', around the fire-box at the front end. These spaces b' are 60 connected by return-flues b*, as shown. A grate-surface, B*, is provided in box B, having suitable supports, as shown.

In space b, secured to the walls of the boiler-body and so placed as to lie partially over the 65 open end of the fire-box, is the curved or inclined heater or water-back E. This heater is formed of two sheets of boiler-iron, held together and supported by the stay-pins e e, as shown. The top of the heater is secured to 70 the top of the fire-box and the sides to the walls of the boiler-body by means of flanged edges, with which it is provided, and bolts or rivets.

Situated over the upper portion of the mouth 75 of the fire-box, and extending well down it, and approaching close to the rear end or head of the boiler, the heater, as will be readily appreciated, is in the best possible position to receive the full benefit of the heat and flame 80 from the fire-box, as the same will flow out and strike the heater with full force, and then be compelled to flow down it and around its end or lower side, and thence the natural upward tendency of the heat and flame will carry it 85 upward over the outside of the heater, and the return-flues b* will induce another turn and draw the said heat and flame downward to be carried off after having imparted to the water in the heater an intense degree of heat. 90

Circulation for the heater is made in the most careful and efficient manner. It receives the water through pipe f from the lower portion of the boiler, thus taking the colder strata of the boiler water. This it receives, as 95 shown, into the lower part of it, and where it will become at once hot, and rise in the heater. After receiving the proper degree of heat the water flows out through pipe f' into the boiler. The water-supply for the boiler is through the 100 heater by way of pipe G. This pipe f', as shown in Fig. 4, leads from the part E out through the shell and back into the boiler. The water thus taken into the boiler is first

heated to boiling-point in the heater, and when introduced in the boiler, instead of reducing the temperature of the contents thereof, as is usually done, our supply-water tends to increase the same.

Having thus described our invention, what we desire to claim, and secure by Letters Patent, is—

1. In a steam-boiler, the combination, with the fire-box having the water-jacket surrounding it, of a water-heater chamber consisting of a receptacle, substantially as described, placed directly over the end of the fire-box in a sloping position, and having a connecting-pipe, as ¹⁰ ₁₅ *f*, extending from said heating-chamber to the boiler or water-jacket beneath the fire-box, and a connection, as *f'*, near the top of said chamber, extending into the water-jacket at that point, as set forth.

2. In a steam-boiler, the combination, with the water-containing portion of the boiler, a fire-box surrounded by said water-containing portion, and a space, as *b*, at the end of the fire-box, divided from the water-containing portion, of a water-heating device placed in said ²⁰ ₂₅ space *b*, and extending from the top of the fire-box downward in a curved or sloping position, and almost touching the rear wall of said space, and having connections *f f'* to the water-containing portion, and a water-supply, as ₃₀ *G*, substantially as set forth.

In testimony whereof we affix our signatures in presence of two witnesses.

JOHN M. DUNN.
WILLIAM E. SIDWELL.
